INVENTOR
VICTOR PARKIN:

BY

R. S. Bown
ATTORNEY

UNITED STATES PATENT OFFICE.

VICTOR PARKIN, OF PATTON, CALIFORNIA.

DESIGN FOR AN ORANGE-PEELER.

• 56,678.

Specification for Design.

Patented Nov. 23, 1920.

Application filed March 25, 1920. Serial No. 368,763. Term of patent 7 years.

To all whom it may concern:

Be it known that I, VICTOR PARKIN, citizen of the United States, residing at Patton, county of San Bernardino, and State of California, have invented a new, original, and ornamental Design for an Orange- Peeler, of which the following is the specification, reference being had to the accompanying drawing, forming a part thereof.

Figure 1 is a perspective view;
Fig. 2 is a side elevation; and
Fig. 3 is an end view, showing my new design.

I claim:

The ornamental design for an orange peeler, as shown.

VICTOR PARKIN.
